UNITED STATES PATENT OFFICE.

EDWARD GUY GOBEN, OF BROOKLYN, NEW YORK.

PROPELLING AND SMOOTHING DEVICE.

Application filed February 19, 1923. Serial No. 620,090.

This invention relates to a propelling and smoothing device and is particularly adapted to operate in conjunction with the cutting machine for cloth and other material described in Patent #1,380,710, dated June 7th, 1921.

The object of the invention is the production of a device that will smooth and eliminate wrinkles from various fabrics and other pieces of material, so that they can be efficiently operated upon in a printing press. A second object of the invention is the production of a device that will carry pieces of material to a printing press cylinder and which will simultaneously smooth them. Other objects will be evident from the following specification.

The organization of the invention comprises a moving apron to carry the material operated upon and a plurality of moving feeding tapes bearing upon the material. The coaction of the apron and tapes will propel and smooth the material operated upon.

In the accompanying drawings Fig. 1 represents a side elevation of the propelling and smoothing device with a side elevation of a cutting machine and fragmentary portion of a printing press with which it operates; Fig. 2 shows an elevation of a detail and Fig. 3 indicates a top plan view of Fig. 1.

A fragmentary portion of a printing press is indicated with the side frames 20 and 21, in which is journaled the shaft 22. A printing press cylinder 23 and the spur gear 24 are fastened to the shaft 22. The cylinder 23 is provided with the usual grippers 27. A spur gear 28 is fastened to the shaft 22. A stud 29 is fastened to the frame 21 and has journaled thereon the spur gear 30 which meshes with the spur gear 28. A sprocket chain wheel 31 is journaled on the stud 29 and turns with the spur gear 30.

Supporting beams 32 and 33 of a cutting machine are supported upon and fastened to the side frames 20 and 21. Side housings 39 and 40 are respectively supported upon the beams 33 and 32 and are fastened thereto by means of the bolts 41. The housings have each formed therewith the horizontal guides 42 for the adjustable journal boxes 43, and the vertical guides 44 for the journal boxes 45. A roller shaft 46 with the side roller 47 is journaled in the journal boxes

43, and a roller shaft 48 with the top roller 49 is journaled in the journal boxes 45.

A drum shaft 50 has its ends journaled in the side housings 39 and 40 and has fastened thereto the measuring drum 51. A spur gear 52 is fastened to the shaft 50. A journal stud 53 is adjustably supported in the slot 54 of the housing 40, by means of the nut 55. A spur gear 56 and a sprocket chain wheel 57 are detachably connected and journaled on the stud 53. The spur gear 56 meshes with the spur gear 52. Gears of different diameters can be substituted for the spur gear 56, to enable the spur gear 52 and the drum 51 to turn at different speeds, to vary the length of the material cut by the cutting machine. A pair of journal brackets 60 extend from the side housings 39 and 40 and have journaled thereon the guide roller 61.

An idler bracket 62 having the slot 63 is adjustably clamped to side housing 40 by means of the bolt 64. An idler sprocket chain wheel 65 is journaled to the top end of the bracket 62.

A knife shaft 68 is journaled in the side housings 39 and 40 and has fastened thereto the rotary knife frame 69 having adjustably connected thereto the knife blade 70. A stationary knife blade holder 71 has its ends adjustably supported in the side housings 39 and 40. A stationary knife blade 72 is supported on the holder 71. A sprocket chain wheel 73 is fastened to the shaft 68. A sprocket chain 74 extends around the sprocket chain wheels 57 and 73, and the idler sprocket chain wheel 65 bears down on the sprocket chain 74.

An inclined feeder 78 is indicated with the horizontal ends 79 and the latter are detachably fastened to the side housings 39 and 40 by means of the bolts 80.

A flange bushing 83 is fastened to the knife shaft 68. A sprocket chain wheel 84 with elongated slots 85 is adjustably connected to the bushing 83, by means of the screws 86.

Sprocket chain wheels 90, 91 and 92 are journaled to the beam 33, and a sprocket chain wheel 93 is journaled to the housing 39. An arm 95 having the elongated slot 96 is adjustably fastened on the outer face of the supporting beam 33, and has journaled thereto the sprocket chain wheel 97.

A knife shaft driving chain 102 extends

around the sprocket chain wheels 84 and 31 and bears against the sprocket chain wheels 90, 91, 92, 93 and 97. The shaft 68 receives rotation from the sprocket chain wheel 31, by means of the sprocket chain 102. The knife shaft 68 rotates at the same speed as the shaft 22 of the printing press cylinder 23. The printing press cylinder 23 and the knife blade 70 are maintained in proper operative relation by means of the adjustably connected sprocket chain wheel 84.

Upon the supporting beams 32 and 33 are fastened the journal bearings 105 and have journaled therein the shafts 106 and 107 which are axially in line. A wooden apron drive roller 108 is fastened to the shafts 106 and 107. A sprocket chain wheel 109 is fastened to the shaft 107 and connects with a feeding device, not shown. A pulley 110 is fastened to the shaft 106. A sprocket chain wheel 111, is fastened to the shaft 107. A sprocket chain wheel 112 is fastened to the drum shaft 50. A sprocket chain 116 connects the sprocket chain wheels 111 and 112, and rotation is thereby transmitted from the drum shaft 50 to the shafts 106 and 107.

A pair of journal brackets 122 are supported on the beams 32 and 33 and have journaled thereon the tape wheel shaft 123. A pulley 124 is fastened to the shaft 123 and a cross belt 125 connects the pulleys 110 and 124, to transmit rotation from the shaft 106 to the shaft 123. A plurality of pulleys 128 are fastened to the shaft 123.

A pair of journal brackets 130 are clamped to the inner faces of the beams 32 and 33, by means of the bolts 131, which can engage different openings 132, 133 and 134 in said beams, for the purpose of maintaining the apron 136 to be described at the requisite tension. A roller 135 is journaled in the brackets 130. An endless apron 136 is supported by the rollers 108 and 135.

A pair of adjustable journal brackets 140 are fastened to the inner faces of the supporting beams 32 and 33 by means of the bolts 144 and have journaled therein the shafts 141 and 142 which are axially in line. A wooden idler roller 143 is fastened to the shafts 141 and 142.

A pair of journal brackets 148 are fastened to the top faces of the lower ends of the beams 32 and 33. A tape wheel shaft 150 is journaled in the brackets 148. Pulleys 151 are fastened to the shaft 150, and feeding tapes 152 connect the pulleys 151 and 128. The wooden roller 143 bears on the lower members of the tapes 152 to locate said lower members in proper operative position relatively to the apron 136.

To operate the propelling and smoothing device rotation is imparted to the spur gear 24, and thereby the printing press cylinder

23 is turned. The spur gear 28 rotates with the cylinder 23 and thereby rotation is transmitted to the spur gear 30. The material, in this instance the cloth 155, is delivered from a feeding device to the guide roller 61, 70 passes under the side roller 47 and from the latter passes upon the measuring drum 51 and extends over the fender 78. The material 155 is next severed by the knife blades 70 and 72 in proper lengths, depending upon 75 the speed of the measuring drum 51. The severed pieces 155^a of the material 155 slide down the feeder 78 and drop upon the endless apron 136 and are carried to the printing press cylinder 23. The linear speed of the 80 apron 136 equals the circumferential speed of the material on the measuring drum 51. The cut pieces of material 155^a are fed between the top member 136^a of the apron 136 and the lower members 152^a of the feeding 85 tapes 152. The members 152^a and 136^a form a plurality of feeding nozzles 152^c for the cut pieces of material 155^a. The angle between the members 152^a and 136^a, as well as the pressure between the members 152^a and 152^c and the material operated upon can be varied by locating the idler roller 143 in different positions. This is accomplished by 90 locating the brackets 140 in different positions by means of the bolts 144. The cut 95 pieces of material are carried to the press cylinder 23 where their forward ends are gripped by the grippers 27, and they are next delivered to a folding machine, not shown. In case the forward ends of the cut 100 pieces of material 155^a are turned up or wrinkled they are smoothed out by the co-action of the member 136^a of the apron 136 and the members 152^a of the feeding tapes 152, by reason of the said tapes running at a 105 speed about double the speed of the apron 136. In case the forward ends of cut pieces of material 155^a operated upon, are turned down, the member 136^a of the apron 136 continuously running forward, causes the turned-down ends to be straightened out. By 110 this means the cut pieces of material 155^a are delivered to the printing press cylinder 23 in proper form.

Various modifications may be made in the invention without departing from the spirit thereof and the present exemplification is to be taken as illustrative and not limitative thereof.

Having described my invention what I desire to secure by Letters Patent and claim is:

In a propelling and smoothing device the combination of a pair of supporting frames, a drive roller journaled at one end of the frames, a pair of adjustable brackets bolted to the other end of the frames, a plurality of openings in the frames for the bolts of the latter brackets to clamp them in different positions, a roller journaled in the ad- 120 125 130

justable brackets, an endless apron supported on said rollers, said apron adapted to carry pieces of material operated upon, means to turn the drive roller, a second pair 5 of journal brackets supported on the supporting frames, a tape wheel shaft journaled in the second pair of brackets, means to turn the tape wheel shaft, a plurality of pulleys fastened to the latter shaft, a third pair of 10 journal brackets fastened to the supporting frame, a tape wheel shaft journaled in the third pair of journal brackets, a plurality of pulleys fastened to the latter shaft, feeding tapes supported upon and connecting the 15 pulleys of one shaft with the pulleys of the other shaft, a fourth pair of adjustable journal brackets fastened to the frames, a shaft journaled in the latter brackets, a roller fastened to the latter shaft, the latter roller bearing on the lower member of the 20 feeding tapes and leading the lower member of each tape to take an inclined direction to said apron, to form a plurality of feeding nozzles therewith for the pieces of material operated upon and means to move the tapes 25 at a different speed than said apron.

Signed at the borough of Manhattan, city of New York in the county of New York and State of New York this 15th day of February A. D. 1923.

EDWARD GUY GOBEN.
